US00D720312S

(12) **United States Design Patent**
Shiroyama et al.

(10) **Patent No.:** US D720,312 S
(45) **Date of Patent:** ** Dec. 30, 2014

(54) **COAXIAL WAVEGUIDE CONVERTER
SUBSTRATE WITH FILTERING FUNCTION**

(71) Applicants: **NEC Engineering, Ltd.**, Shinagawa-ku, Tokyo (JP); **NEC Corporation**, Minato-ku, Tokyo (JP)

(72) Inventors: **Norihisa Shiroyama**, Shinagawa-ku (JP); **Kiyotake Sasaki**, Shinagawa-ku (JP); **Sumio Ueda**, Shinagawa-ku (JP); **Takahiro Miyamoto**, Minato-ku (JP)

(73) Assignees: **NEC Engineering, Ltd.**, Tokyo (JP); **NEC Corporation**, Tokyo (JP)

(**) Term: **14 Years**

(21) Appl. No.: **29/488,062**

(22) Filed: **Apr. 15, 2014**

(30) **Foreign Application Priority Data**

Oct. 17, 2013 (JP) 2013-024222

(57) **CLAIM**

The ornamental design for a coaxial waveguide converter substrate with filtering function, as shown and described.

DESCRIPTION

FIG. 1 is a top plan view of a coaxial waveguide converter substrate with filtering function showing our new design; FIG. 2 a bottom plan view thereof; FIG. 3 is a left side elevation view thereof; FIG. 4 is a right side elevation view thereof; FIG. 5 is a front elevation view thereof; FIG. 6 is a rear elevation view thereof; and, FIG. 7 is a perspective view thereof.
